(57) **CLAIM**

The ornamental design for an electronic device, as shown and described.

DESCRIPTION

FIG. 1 is a top, front, right perspective view of an electronic device, showing our new design;

FIG. 2 is a bottom, rear, left perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

Surface appearance contrast is shown by line shading, dense stipple shading, and sparse stipple shading.

The broken lines of even length shown in the drawing illustrate portions of the electronic device that form no part of the claimed design.
